VAPOR COMPRESSION DISTILLATION APPARATUS

Filed April 10, 1946

UNITED STATES PATENT OFFICE

2,515,013

VAPOR COMPRESSION DISTILLATION APPARATUS

Edward R. Kruhmin, Hamilton, Ontario, Canada

Application April 10, 1946, Serial No. 661,130

1 Claim. (Cl. 202—180)

1

My present invention relates to an improved vapor compression distillation apparatus and more particularly to a distilling apparatus employing differential pressure within the apparatus for condensing the steam vapors from the fluid under distillation.

According to my invention, the raw material is passed to a concentrate separator, thence to a turbine compressor and thence to a super heater. The superheated steam is then passed to condensing and cooling means where the pure liquid is obtained.

Other and more specific advantages and details of operation will be disclosed hereinafter.

In the accompanying drawing I have illustrated one complete example of the physical embodiment of my invention according to the best mode I have thus far devised but it will be understood that various changes and alterations may be made in the exemplified structure within the scope of the appended claim.

In the drawings:

The figure is a diagrammatic view of the apparatus of my invention.

Referring now to the drawing in detail, I have shown a container 1 for the raw material having an outlet pipe 2 and a valve 3. Pipe 4 from the valve connects with an evaporator vacuum regulator 5 and the pipe 6 passes through the hydrometer 7 to the separator 8. A heating chamber 9 is furnished with a gas burner 10 and the gas therefor is fed through pipe 11 from a source of supply.

Steam gauge 12 is provided on the separator casing and pipe 13 carries vapor to the compressor turbine 14 and the compressed vapors pass through pipe 15 to the superheater 16. This superheater 16 includes an upper air intake 17 and a preheater 18 for the air which then passes through the pipe 19 to the fire box. The fire in the fire box supplies heat for the superheater coil 20 connected with pipe 15 and from the coil the steam passes through pipe 21 to the turbine motor 22. A shaft 23 operably connects the turbine motor operated by the steam from the superheater with the compressor 14.

Steam leaving the turbine 22 passes through pipe 24 past gauge 25 through heat exchange chambers C and A and thence to thermostat 26 and outlet pipe 27, as a distilled product.

Within the separator 8 I employ a bracket 28 supporting the pivotal arm 29 and the float 30. A valve rod 31 attached to the pivotal arm connects below with a valve 32 and the valve 32 is connected with the pump 33. The withdrawn

2

concentrate from the pump 33 passes through a nipple 34 having a valved outlet 35 to pipe 36, and the other side of the nipple connects with pipe 37 leading through the raw solution pre-heater B.

In operation a small fire is started in the superheater and an amount of raw solution is admitted to the separator 8. The gas burner 10 is ignited and steam vapors from the separator pass to the compressor 14 to the superheater coil 20. The steam expands in the coil and then moves to the turbine motor 22 operating the same. The operation of the turbine motor supplies through shaft 23 motive power for the compressor and more steam will be passed therethrough now under pressure. The steam from the turbine then passes to the condenser C to the raw solution pre-heater A and then to discharge.

Under some circumstances it may be desirable to provide a radiator R for the pipe 13 to supply additional heat to the vapors in the pipe prior to entrance into the compressor when the operation is in its initial stages. After the compressed vapors have been superheated, no additional heat will be required, and it has been found that under certain conditions, the gas burner 10 may be cut off and the operation will continue due to the pressure of the compressor on the vapors, the raw solution having been preheated in its passage through chambers A, B, and C.

Having thus fully described my invention, what I claim as new and desire to secure by Letters Patent is:

A distillation apparatus comprising: A feed container for feed liquid; indirect heat exchange means; conduit means for passing the feed liquid from the feed container to said indirect heat exchange means; a vaporization chamber; conduit means for passing the feed liquid from said heat exchange means to the vaporization chamber; a liquid level control valve in the vaporization chamber; a liquid outlet in the vaporization chamber, said liquid outlet being controlled by said valve and acting to remove liquid residue from the vaporization chamber; a conduit for passing said liquid residue from the liquid outlet to said indirect heat exchange means; thereby permitting the liquid residue to preheat the feed liquor; means for removing the liquid residue from the heat exchange means; a vapor outlet in the vaporization chamber; a vapor compressor; means for passing the vapors from said vapor outlet to the vapor compressor; a superheater; means for passing the vapors from the vapor compressor to the superheater; heating means in the superheater for heating the vapors; a turbine;

means for passing the vapors from the superheater to the turbine; the turbine being connected to the vapor compressor to drive the vapor compressor; conduit means for passing the vapors from the turbine to said indirect heat exchange means, the vapors being condensed in the indirect heat exchange means and thereby acting to preheat the feed liquid; and means for removing the condensate from the indirect heat exchange means.

EDWARD R. KRUHMIN.
